BABY CHAIR

Edward Hugh Clairmonte and Clive Molyneux
Clairmonte, London, England

Application June 11, 1946, Serial No. 675,891
In Great Britain July 24, 1945

5 Claims. (Cl. 155—38)

1

This invention consists in improvements in or relating to baby chairs of the type which may be used in an erect position as a high chair, or in a folded position as a low chair.

The invention has for its object to provide a baby's chair of the type described of simple construction which may readily be converted from the erect position to the folded position and vice versa.

Accordingly, the invention provides a baby chair of the type described wherein the seat is carried by a pair of supports, each support comprising a leg portion and a base portion, the leg portion being hinged intermediate its length to permit the base and lower part of the leg portion to be swung towards the seat from the erect position to the folded position, means to limit the swinging motion such that the lower leg constitutes a base for the chair in said folded position, and locking means to lock the parts of the legs in the erect position.

Conveniently, said means to limit the swinging motion is constituted by a cross-bar connecting the base portions of the supports which bears against the seat in the folded position of the chair.

In one construction, according to the invention, each support is a tubular metal member shaped to provide a leg portion and base portion, the leg portion comprising intermediate its length a hinge which is such that, when the chair is in the erect position the parts of the leg portion are resiliently locked in alignment. A convenient form of hinge comprises a pivot pin secured to one part of the leg portion engaged in a slot in the other part of the leg portion, inter-engaging locking surfaces formed on said leg portions, and spring or the like means urging the locking surfaces into engagement.

Conveniently, the seat is of the bucket type and is constituted by one or more pressings, for example, sheet metal pressings, secured together, and there is provided a channel between the base of the seat and the back thereof whereby liquids spilt on the seat drain into the channel and may be readily wiped up.

Other features of the invention will be apparent from the following description which has reference to the accompanying drawings, of one construction of baby chair embodying the invention.

Referring to the drawings,

Figure 1 is a perspective view of the baby chair in the erect position,

Figure 2 is a side elevation of a baby chair in the folded position,

2

Figure 3 is a sectional elevation on an enlarged scale of the seat of the chair.

Figure 4 is a detail view of a suitable form of hinge for connecting the upper and lower leg parts, and

Figure 5 shows a modified method of securing the seat upholstery.

The baby's chair comprises a seat 1 of the bucket type carried by a pair of supports, each of which is formed with a leg portion and a base portion, the leg portion having an upper part 2a to which the seat is secured and a lower part 2b hingedly connected to the upper part 2a. The lower part 2b of the leg and the base portion 3 are formed in one piece being connected by a radiused portion 4 and being inclined to one another at an angle of about 75°, so that the seat 1 is located above the base portion 3, in the erect position. In the erect position of the chair, the upper and lower parts 2a, 2b of the leg are held in alignment (see Figure 1) while in the folded position (see Figure 2) the lower parts 2b provide a base for the chair, while in the folded position of the chair, the base portions 3 extend on either side of the seat 1, there being a cross-bar 5 connecting the base portions 3 and located in such a position that it limits the extent to which the parts 2b, 3 may swing towards the seat 1 by bearing against the underside of the seat 1 whereby in the folded position the parts 2b provide a base for the chair.

The base portions 3 may be curved slightly upwards towards their centres so that only the front and rear extremities thereof of the base portions 3 make contact with the floor thereby giving stability to the chair on an uneven floor.

A tray 6 is pivoted to a bracket 7 carried by one of the supports and is provided with a spring catch 8 engaging in a bracket 9 in the other support. A foot rest 10 formed conveniently as a metal pressing is attached to the upper legs 2a at a suitable distance below the seat 1 and may be provided with an inset of cork or other suitable material.

The hinged connection between the upper parts 2a and lower parts 2b may be of any suitable form, such that when the chair is in the erect position the parts 2a, 2b are locked in alignment and such that when the parts are unlocked, the lower part 2b and base portion 3 may swing upwardly towards the seat 1 to the folded position.

One convenient form of such a hinged connection is illustrated in Figure 4. Fitted within the ends of the parts 2a, 2b of the leg portions are complementary tubular hinge members 11 which

have lugs 12 formed thereon extending axially of the parts 2a, 2b, and terminating in locking lands 13 which are adapted to engage in locking recesses 14 when the chair is in the erect position. A pivot pin 15 is fixed to the extension 12 of one hinge member 11 and works in a slot 16 formed in the other hinge member. A compression spring 17 housed within the lower part 2b of the leg is connected to the pivot pin 15 by length of strong wire 18 which is bent into U-form to engage over the pivot pin 15, passes through the hinge member 11 and has its ends 19 hooked to engage under the spring. Thus when the chair is in the erect position, the locking lands 13 are engaged with the locking recesses 14 and are held resiliently in engagement by the action of spring 17. To move the parts 2b of the leg portion and base portion 3 to the folded position, the locking lands 13 are disengaged from the locking recesses 14 against the spring 17 for example, by placing a foot on the base portion 3 and lifting the seat 1 and then causing the lower part 2b and base 3 to swing about its pivot pin 15. This motion is facilitated by the radius portion 4.

To convert the chair from the folded position to the erect position, the seat 1 is gripped and raised whereby the parts 2b and base portion 3 will swing under their own weight towards the erect position and when this position is reached the locking lands 13 will snap into engagement with the locking recesses 14. It will thus be seen that the chair may be readily converted from a high chair to a low chair and vice versa.

The seat 1 is conveniently of the bucket type and is formed of one or more pressings, for example sheet metal pressings secured together. A detail section through one suitable form of seat is shown in Figure 3. In this form, the seat comprises two sheet metal pressings one of which constitutes the seat bottom 20 and the other 21 constitutes the seat back and sides, the two pressings 20, 21 being secured together by rivets 22. The bottom has a cushion 23 of any suitable form secured thereon. Between the seat bottom 20 and the back and sides 21, there is provided a channel 24 into which liquids spilt on to the seat drain and are readily wiped up and which facilitates cleaning of the seat. The upholstery of the back and sides is secured in position in any desired manner, but conveniently the fabric covering 25 is gripped along its lower edge between the flange 26 on the bottom 20 and the back pressing 21, the rivets passing through the fabric covering 25, and is gripped along its upper edge between the seat back 21 and a strip of metal 27 which is held in place by rivets 28.

Where the bucket seat is made from a single pressing, the fabric covering 25 may be held in a similar manner along its upper edge, while the lower edge is, for example, formed with a loop 29 through which a curved blade spring or strip of stiff material 30 is passed, the strip being sprung into the bucket seat to which it may also be secured by rivets or the like means so as to hold the lower edge of the upholstery material securely in position.

The bucket seat may be made from any suitable material such as metal pressings or mouldings, or mouldings of such materials as plastics.

The parts of the chair may be formed of metal or parts may be formed of metal and parts of non-metallic material. Suitable metals are steel, aluminium or other aluminum alloys and suitable non-metallic materials are wood and plastics.

The supports are preferably of steel tubing thereby avoiding sharp corners on which the child could hurt itself.

It will be seen that the invention provides a baby chair of simple form, which is easy to clean and may be readily converted from a high chair to a low chair or vice versa.

We claim:

1. A two-position baby chair comprising a pair of legs each including an upper part, a lower part, and a base portion, said upper and lower parts being in axial alignment when said chair is in high-seat position, a seat rigidly secured to the upper ends of said upper leg parts, said legs constituting the sole support for said seat in high-seat position, members carried on the adjacent ends of the respective upper and lower parts of each leg and engageable, by relative sliding movement, to maintain said leg parts rigidly in alignment, means pivotally connecting the members on each leg and slidably relative to one member on each leg to permit disengagement of the interlock therebetween and swinging movement into low-seat position of the lower leg portions relative to the upper leg portions, and means to limit such swinging movement at a position in which said lower leg parts are substantially parallel to the bottom of said seat.

2. A baby chair as claimed in claim 1, including resilient means urging said members into interlocking engagement.

3. A baby chair as claimed in claim 1, said limiting means comprising a cross-member connecting said base portions and engaging the bottom of said seat when the device is in low-seat position.

4. A baby chair as claimed in claim 1, the leg parts and base portions being formed from tubular metal, the means pivotally connecting the members on each leg comprising a pivot pin carried by the member carried on the end of said upper part of the respective leg and engaging an axially-directed slot in the member carried on the end of the lower part of the leg, and a spring accommodated within said lower part of the leg and connected to said pivotal means to urge said parts of the leg axially together.

5. A baby chair as claimed in claim 1, the legs and base portions being formed from tubular metal, said pivotal means being secured to a part fitted in and extending axially beyond the end of said upper leg part, and including a spring accommodated within said lower part of the leg and connected to said pivotal means to urge said parts of the leg axially together.

EDWARD HUGH CLAIRMONTE.
CLIVE MOLYNEUX CLAIRMONTE.
